Application March 8, 1935, Serial No. 10,002

3 Claims. (Cl. 36—8.5)

This invention pertains to footwear and relates more particularly to shoes designed to prevent or to correct certain common foot ailments, although it is to be understood that the utility of the invention in its broader aspects is not restricted to such corrective shoes.

One common foot defect, known as pronation, is a tendency of the foot to roll inward so that the weight is no longer properly supported upon the insole of the shoe but rests in part upon the shoe upper at the inner edge of the insole. To correct this tendency it has heretofore been proposed to provide an insole with an extension projecting from its inner edge along the instep, such projection being so shaped, for example during lasting, as to constitute a guard, operative to bear against the inside surface of the foot and to support the foot in opposition to its tendency to roll or flow inwardly. However, such extension of the insole is not altogether adequate for the purpose, since in resisting the pressure of the foot, such extension acts, speaking in mechanical terms, substantially like a beam supported at one end, the character and form of the upper material at this point being such as to lend little effective support to the outer upper part of this extension. In consequence such insole extension soon loses its strength and lasted shape, particularly when moist, and thus can not be depended upon for any length of time to function as intended, even if stiff and fairly effective when the shoe is new.

In accordance with the present invention, the desired supporting and guarding action is obtained by extending the usual stiff counter member forwardly along the inside of the shoe to a point which preferably is adjacent to the forward end of the shoe shank,—the lower part or flange of the counter being firmly anchored in the shoe bottom structure throughout its entire length. Since the counter is of substantial depth, and at its rear end is sharply arched (in horizontal section), the counter extension strongly resists deformation and thus provides a substantial support for the foot along the shank portion of the shoe.

In order to provide as smooth and uninterrupted a foot supporting surface as is possible and at the same time to take advantage of such additional supporting action as may be obtainable from the upper of the shoe, it is proposed, in accordance with the present invention, to arrange the forward extension of the counter at the inner side of the shoe lining,—the quarter lining being slit at a suitable point forward of the heel

to allow the counter to protrude to the interior of the shoe. In this way the hard surface of the insole directly merges with the hard surface of the counter, and if one or both of the meeting surfaces be thin, beveled or skived, a substantially uninterrupted, rigid, stiff and strong curved foot-supporting surface is obtained.

Furthermore, as the extension of the counter is inside of the lining, both the lining and the outer member of the upper assist, to some extent at least, in bracing and retaining the lasted shape of the counter extension.

While the counter extension, provided as above described, is useful and in most cases wholly adequate for the intended purpose, it is proposed in accordance with this invention further to brace it and assist it in resisting outward pressure of the foot. To this end the upper is furnished with a suspension element or sling, for example a strip of substantially inextensible material such as woven or braided webbing firmly anchored to the top edge of the upper as, for instance, at a point adjacent to the vent and extending downwardly to a lower point of anchorage in the shoe bottom structure, such sling preferably being disposed between the lining and the outer element of the upper and being so located that the free forward end of the counter extension is overlapped and girded by this sling. In a preferred construction, this sling is a bifurcated member of inverted V-shape, having its upper member anchored, as described, to the top portion of the upper, and having the ends of its downwardly divergent arms anchored to the shoe bottom structure, said arms passing down on the outer side of the counter extension and helping to prevent outward bulging of the latter.

When, with such a construction, the shoe is snugly laced, the sling is placed under tension and, by reason of its inextensible character, effectively prevents outward bending of the counter extension when subjected to the pressure of the foot. This reinforce sling has a further advantage, during the process of manufacture, since its lower end (or ends) affords a convenient element to be grasped by lasting pincers in applying lasting strain to the upper, and by reason of the strong and inextensible character of the sling, it is thus possible to exert force to last-in the forward end of the counter extension against the wood of the last, which is not easy to do by applying lasting stress directly to the upper material alone.

Among the contributing factors to many foot ailments is the constriction by the shoe of the

blood vessels of the foot so that normal and adequate supply of blood to the tissues of the foot is interfered with. Some of the more important blood vessels are located at the top of the foot 5 very near the surface and just where the shoe laces cross from one side to the other. Thus, if a shoe, particularly when provided with the suspension or sling device above described, is tightly laced (as it must be for effective action of the 10 sling), the laces tend to press into the top of the foot to such an extent as seriously to interfere with the blood circulation as well as to cause discomfort to the wearer. To avoid this difficulty, the quarter lining, which, as above noted, 15 is slit near its rear end to permit protrusion of the counter extension, differs further from the usual quarter lining in having its forward parts, that is to say, those parts which receive the lacing eyelets, made of or including a soft, cushion element, for example, felt or the like, into which the lacing readily sinks so that the top of the foot is relieved of constrictive localized pressure. Thus not only is the foot, if initially abnormal, adequately supported against tendency 20 to turn or roll inwardly (pronate) but the conditions which might lead to such abnormality or other undesirable and troublesome foot ailments are eliminated.

Other and further objects and advantages of 30 the present invention will be pointed out and may be hereinafter referred to in the more detailed description appended hereto and by reference to the accompanying drawings, in which

Fig. 1 is a perspective view of a shoe for the 35 right foot, embodying the present invention and having a portion of the upper at the right-hand or outer side of the shoe broken away and in section to show the interior construction, the heel pad being removed;

Fig. 16 is a view similar to Fig. 1, showing the

device of Fig. 15 embodied in a shoe and showing the heel pad in place;

Fig. 17 is a section substantially on the line 17—17 of Fig. 16;

Fig. 18 is a plan view of a preferred form of 5 heel pad useful in shoes such as shown in Figs. 1 and 16, for example;

Fig. 19 is a broken perspective, partly in section, of a shank wedge useful in the practice of 10 the invention;

Fig. 20 is a side elevation, to smaller scale, of the shoe shown in Fig. 1, but viewed from the opposite side;

Fig. 21 is a plan view of a blank useful in making a sling of the kind illustrated in Fig. 16; and 15

Fig. 22 is a rear view of the same blank, after folding, and in readiness for use in a shoe.

Referring to the drawings, the numeral 1 designates a shoe embodying the present invention,—the shoe illustrated being a man's shoe for the 20 right foot and comprising the upper U, the outer sole S, the heel H, the lace L, and the inner sole 2.

The quarter of the shoe upper comprises the outer member 4, which may be of leather or other suitable material, the quarter lining 5 and the 25 counter 7. This counter, as illustrated in Fig. 4, is a stiff, moulded counter made from leather, fiber board, or such other material as is appropriate for such purpose and has the flange 8 at its lower edge adapted to be secured against the 30 under surface of the inner sole. The counter also comprises the side wall 9 of approximately the usual length, such as to terminate at about the plane of the breast of the shoe heel, the wall 9 being that which is disposed at the outer side 35 of the foot, that is to say, the right-hand side of the shoe shown in Fig. 1. The side wall of the opposite side of the counter comprises the forwardly directed extension 10 adapted to reach along the shank portion of the shoe, if desired, 40 substantially to the ball of the foot, such forward extension 10 preferably terminating in a smoothly curved edge 11 which is concave rearwardly. 45

In accordance with the present invention the quarter lining 5 is provided with a slit 12, preferably curved, through which the extension 10 of the counter emerges from the outside of the lining 4 to the inner side of the latter. This slit 12 preferably is curved in such a way that the rear end 13 of the exposed portion of the counter 50 is concave forwardly on such an arc that the exposed portion of the counter, viewed from the inside of the shoe, is substantially symmetrical. However, the exact shape of the end 13 of the counter extension are not substantially material and may be varied as desired. 55

The quarter, if desired, may comprise a doubler 14 interposed between the outer member and the lining, such a doubler being indicated in Fig. 7 60 as interposed between the outer member 1 and the lining 5. This quarter lining 5 may be of any suitable material, for example leather, particularly at that part which embraces the heel of the foot, and is united to the vamp lining 16 by 65 means of a seam 15 in the usual way. The forward or vent portions of the quarter lining are provided with the usual eyelets 18 for the reception of the lace L, and in accordance with the present invention these vent portions preferably 70 comprise lining members 19 of felt, napped fabric, velvet or other suitable soft cushioning material, replacing the lining member 5 at this part of the lining and being united to the member 5 by a seam 20. 75

In accordance with one embodiment of the present invention I provide a strap, girder, or sling device 21 interposed between the cushion element 19 of the quarter lining and the outer member 7 of the quarter at this point. This strap 21 is preferably of some substantially inextensible material such as a woven or braided tape, canvas or the like and, if desired, may be united at its upper edge to the cushion member 19 by a seam 22, such seam being substantially parallel to the edge 17 of the vent portion of the upper. Certain of the eyelets 18^a for example, may pass through the upper part of this strap 21 and serve to anchor the latter very firmly to the outer member 7 as well as to the cushion member 19. If desired, the seam 22 may be omitted. As illustrated in Figs. 7 and 8, the strap 21 extends down below the lower edge of the shoe upper before lasting, and this extended portion of the strap forms a convenient means for applying stress to the upper during lasting, thereby to draw the lining firmly against the wood of the last.

The strap 21 is disposed at such a point in the shoe upper that when it is tensioned during the lasting operation, the strap overlaps the forward end at least of the extension member 10 of the counter. Thus by applying tension to this strap, the forward edge of the extension 10 may be drawn in very forcibly toward the side of the last.

In Figs. 12, 13 and 14 certain steps in the lasting operation are illustrated.—Fig. 12 showing the inner sole 2 and the upper with its strap 21 assembled upon the last and held in spindled relation by the tack T at the rear end of the upper. After the assembly of the parts in this way, the upper is pulled over and the tacks 24 inserted at the toe. Following this operation, the laster may seize the end of the strap 21 and apply tension to the strap such as to pull it up and inwardly over the last bottom, thereby drawing in the lining member 5 and the extension 10 of the counter so that the latter is brought into very intimate contact with the wood of the last. The tension on the strap 25 may be exerted in the general direction of the arrow A in Fig. 13, and when the parts of the upper have been pulled in as snugly as desired, a tack 25 may be inserted through the strap, thereby to hold the parts in the lasted position.

The lasting operation is then completed in accordance with any desired method, and if the shoe is to be a welt shoe, the welt W (Fig. 14) will be sewed onto the insole by means of the stitched seam 26. The stitches of this seam will pass through the strap 25, thus permanently anchoring the latter in position to the bottom structure of the shoe, and the tack 25 may then be withdrawn, if desired. If the shoe be of other type, for example a McKay shoe, the tack 25 may be left in place to form a permanent anchorage for the strap, or the strap may be cemented or stapled in position in accordance with other methods of shoe manufacture.

When the shoe is removed from the last, the extension 10 of the counter will be exposed to view on the inner side of the shoe substantially as illustrated in Fig. 1. Preferably a heel pad of the usual finished and soft leather is inserted at some time after lasting. This pad is desirably of the general shape illustrated in Fig. 18 so as to cover at least the heel and shank portions of the inner sole in accordance with usual practice. Preferably, however, the heel pad 28 is furnished with a side flap 29 which is adapted to lie in contact with

and substantially to conceal the unfinished inner surface of the extension 10 of the counter.

However, in order that purchasers may be able to identify the improved shoe construction herein described, I may prefer to provide the flap 29 with a window 29^a, that is to say, a hole having its edge properly finished and, if desired, having a window pane of thin Celluloid or similar material so as to expose a portion of the counter extension to view. This exposed portion of the counter may conveniently form a surface for the reception of a trade-mark or other identifying characteristic.

Referring to Fig. 6, which is a diagrammatic transverse section of a left shoe substantially at the shank portion of the latter, the upper is indicated at U, the insole at 2, the shoe laces at L, and the forward extension of the counter at 10. When the lace L is drawn tightly to cause the upper snugly to embrace the foot, it exerts inward tensile stresses in the direction of the arrows 30 and 31, and these in turn produce tension in the upper in the direction of the arrows 32 and 33 near the junction of the upper with the bottom structure. These tensile forces, exerted by and through the upper, tend to push the counter extension 10 inwardly with a compressive stress, as indicated by the arrow 34, against the foot of the wearer, thus effectively opposing any tendency of the foot to roll inwardly or pronate. However, the application of tension in this manner, as by means of the strap 21, above described, which is interposed between the outer member of the upper and the counter extension, results in the establishment of downward compressive forces, indicated by the arrows 35 and 36, upon the top of the wearer's foot, and, as previously noted, these compressive forces, acting upon the upper surface of the foot, which is not by nature intended to sustain such forces or pressures, may seriously interfere with the blood circulation if these pressures are unduly localized.

To avoid the transmission of this pressure through the individual eyelets or laces to the upper surface of the foot, as is the tendency when the laces are drawn up snugly, I prefer to employ the cushion elements 19 at the forward or vent portions of the quarter lining, as above described.

Referring to Figs. 10 and 11, it may be noted that the inner flanges of the eyelets 18 sink down into this soft, cushion-like material 19 so that they lie below the normal surface of the latter. Likewise when the laces L are drawn tight, so as to bring the edges 17 of the vent portions of the quarter into intimate relationship, the laces themselves sink down into the cushion material 19, as shown in Fig. 11, so that the laces do not exert localized pressure upon the top surface of the foot, the pressure being distributed more or less uniformly over the upper part of the foot so that the blood vessels are not constricted and there is no danger of local injury to the delicate and tender tissues of the foot.

In Figs. 15, 16 and 17 I have illustrated a preferred form of my strap, girder, or sling device, the strap illustrated in Figs. 15 and 16 being of bifurcated form more or less like an inverted V in shape, having the upper part 21^a which is anchored between the inner and outer parts of the quarter of the shoe as, for example, by the eyelets 18^a, and having the divergent downwardly directed legs 21^b and 21^c. While preferably of integral one-piece construction, the V-shaped strap or sling may consist of two single straight straps properly overlapped at their upper ends. As illustrated in Fig. 16, the leg 21^c of this strap or sling

device is located at substantially the same point as the single strap or sling 21 above described, while the leg 21^b extends downwardly and rearwardly and girds the mid-portion of the extension 10 of the counter. With this arrangement, the tightening of the shoe lace exerts a forward and upward tensional stress on the upper through the substantially inextensible strap member 21^c, thus holding the central part of the counter extension 10 firmly in place to support the inner arch of the foot, and at the same time assisting in holding the outer part of the shoe quarter smooth and snug and without wrinkles against the foot.

In the shoe shown in Fig. 16, the heel pad 28 is positioned so as substantially to cover that portion of the counter extension which lies within the quarter lining, but through the window 29^a in this heel pad a small portion of the extension 10 is exposed to view for the purpose of permitting 20 ready identification of the shoe construction.

In order that the bottom structure of the shoe may be as rigid as possible at its extreme inner edge at the shank, a wedge member 37 is disposed between the outer and inner soles at this part of 25 the shoe, said wedge member being of leather or other material which is stiff but at the same time capable of being sewed in place by the stitches 38 which attach the outer sole, this wedge piece acting, to a certain degree at least, to extend laterally the supporting action of the steel shank piece, which itself cannot be extended outwardly past the line of stitches.

Preferably, also, the heel is provided, adjacent to its forward, inner corner, with a wedge 39 (Fig. 35 20), which increases the height of the heel at this point, thus tending to tilt the foot outwardly to assist in overcoming pronation.

The bifurcated sling member of Fig. 15 may conveniently be made from a blank 40 of suitable material, for example, canvas, and shaped 40 more or less as illustrated in Fig. 21. This blank may then be folded to provide double thicknesses of material and the plies may be united by adhesive, or by stitches, as illustrated at 41 in Fig. 22.

45 While I have herein illustrated and described certain desirable embodiments of the invention by way of example, I wish it to be understood that my invention is not necessarily to be limited to the precise arrangements here illustrated, and 50 that substitutions of materials and variations in the arrangement and relative location of parts are to be regarded as within the scope of the invention as set forth in the appended claims.

We claim:

55 1. A shoe comprising an upper including a quarter having a lining, an insole and a stiff hard counter having a flange at its lower margin, the rear end portion and one side wall of the counter being covered and concealed by the lining and the 60 lower edge of the counter being anchored in the bottom structure of the shoe, the other side wall

of the counter having an extension disposed at the inner side of the lining and which reaches forwardly substantially to the forward end of the shank, the upper comprising a substantially inextensible sling member disposed between the outer member of the upper and the lining, said sling member being permanently anchored at its upper end adjacent to the vent of the upper and having its lower end anchored in the shoe bottom structure, said sling girding the counter extension adjacent to the forward end of the latter and being operative, during lasting the shoe, to draw the flanged margin of the counter extension snugly against the lower part of the last.

2. A shoe comprising an upper including a quarter having a lining, an insole and a stiff counter having a flange at its lower margin, the rear end portion and that side wall of the counter which lies at the outer side of the shoe being covered and concealed by the lining, the other side wall of the counter having an extension disposed at the inner side of the lining and which reaches forward substantially to the forward end of the shank, the upper comprising fastener means operative to constrict the upper about the foot and also including a substantially inextensible sling device arranged to gird the counter extension and being operative, during lasting, to draw the flanged margin of the counter extension firmly against the last, said sling device being permanently anchored to the upper near the top of the latter and being placed under tension by the operation of the fastener means in constricting the upper about the foot of the wearer, and a cushion element operative to distribute 35 the pressure exerted by the constrictive action of said fastener means and sling device thereby to prevent injury to the upper part of the foot.

3. A shoe comprising an upper including a quarter having a lining, an insole and a stiff counter, the rear end portion and that side wall of the counter which lies at the outer side of the shoe being covered and concealed by the lining, the other side wall of the counter having an extension disposed at the inner side of the lining 40 and which reaches forward substantially to the forward end of the shank, the upper having eyelets along its vent portion, and lace means engaging said eyelets and operative to constrict the upper about the foot, a substantially inextensible 45 sling interposed between the outer member of the upper and the lining and girding the counter extension, said sling being permanently secured to the upper by means of the aforesaid eyelets, and cushioning means at the inner side of the upper at the region of the vent operative to prevent injury to the foot by the action of the lacing means when the upper is constricted about the top of the foot.

ALFRED W. DONOVAN.
